UNITED STATES PATENT OFFICE.

GEORGE H. WEIDNER, OF QUAKERTOWN, PENNSYLVANIA.

FOLDING STOOL AND THE LIKE.

Application filed February 14, 1924. Serial No. 692,717.

To all whom it may concern:

Be it known that I, GEORGE H. WEIDNER, a citizen of the United States, residing at Quakertown, in the county of Bucks and 5 State of Pennsylvania, have invented certain new and useful Improvements in Folding Stools and the like, of which the following is a specification.

My invention consists in a new and useful 10 improvement in folding stools and the like, and is designed to provide a structure which when folded is very compact and when opened affords a well braced oblong platform suitable for use as a seat or for a 15 table. The particularly novel feature of my device is the combination of a central tubular member and a series of fixed and 20 movable collars related thereto carrying the various rods which serve as legs, supports for the platform, and braces therefor.

In the drawings filed herewith I have 25 illustrated one specific embodiment of my invention but it is to be understood that I do not consider my invention limited to the specific embodiment so illustrated but 30 refer for its scope to the claims appended hereto.

In the drawings:

Fig. 1 is a side elevation of my device 35 in open position.

Fig. 2 is a top plan view of my device, a portion of the platform being broken away.

Fig. 3 is a side elevation showing the 40 device folded.

Fig. 4 is a top plan view, the device being folded.

Fig. 5 is a bottom plan view, the device being folded.

Fig. 6 is a detail showing one of the 45 movable collars.

My device has a central tubular member 1 open at its lower end and closed at its upper end by a cap 2 having a series of outwardly extending jaws 3 in which are pivoted arms 4 provided at their ends with bends 5 and slots 6. A collar 7 is slidably received on the member 1 and provided with a series of jaws 8 having cross-pins 50 9 therein, and a boss 10 through which passes a set screw 11 for fastening the collar 7 upon the member 1 in adjusted position. Braces 12 are pivotally attached to the side of the arms 4 and are provided with bends 13 and jaws 14 which embrace the pins 9 when the free ends of the braces 12

are inserted into the jaws 8 on the collar 7. The bends 13 are provided so that the ends of the braces 12 are aligned vertically with the arms 4 so the ends can be inserted into the jaws 8 which are aligned vertically with the jaws 3 on the cap 2.

The member 1 is also provided with a sliding collar 15 to which are pivoted legs 16, and also provided with a set screw 17 for fastening the collar 15 upon the member 1 in adjusted position. The legs 16 are provided at their bottoms with feet 18 turned inwardly to afford a substantial base and also designed to form a closure for the lower open end of the member 1 when the device is collapsed. I provide at the lower end of the member 1 a fixed collar 19 to which are pivotally attached braces 20 pivotally attached also to the legs 16.

In order to provide a top for my device, two rods 21 carrying between them a web 22 of any suitable material are positioned upon the ends of the arms 4 by having their slotted ends received in the slots 6 of the arms 4.

It is to be particularly noted that by reason of the peculiar disposition of the jaws 3 upon the collar 2 the arms 4 are disposed as diagonals of an oblong formed by the rods 21 and the sides of the web 22. Thus it will be seen that I have provided a device in which the top when extended is an oblong instead of a square, which is particularly desirable when the device is to be used as a seat.

When my improved stool is collapsed, the web 22 may be rolled about the rods 21 and then placed within the tubular member 1, being retained therein by the top cap 2 and the feet 18 which close the lower end of the member 1.

Having described my invention, what I claim is:

1. In a folding stool and the like, the combination of a tubular member; a closure cap at one end of said member; arms pivotally mounted on said cap; a pair of rods detachably mounted on said arms; a web carried by said rods; a collar slidable on said tubular member; legs pivotally mounted on said collar; and inwardly turned feet on said legs adapted to provide a cover for the open end of said tubular member.

2. In a folding stool and the like, the combination of a tubular member; a spider fixed at one end of said member; arms piv-

totally mounted in said spider; a collar slide-
able on and rotatable about said member
and provided with brackets; braces pivot-
ally mounted on said arms and detachably
received in said brackets; a second collar
slideable on said member; legs pivotally
mounted on said collar; a second spider

fixed at the other end of said member; and
braces pivotally attached to said spider
and said legs. 10

In testimony whereof I affix my signa-
ture.

GEORGE H. WEIDNER.
